Patented Mar. 30, 1915.

UNITED STATES PATENT OFFICE.

PHILIP H. VOIGT AND OSCAR C. KUEHNE, OF HOUSTON, TEXAS.

WINDING-DRUM.

1,133,592.

Specification of Letters Patent. Patented Mar. 30, 1915.

Application filed November 25, 1913. Serial No. 803,037.

To all whom it may concern:

Be it known that we, PHILIP H. VOIGT and OSCAR C. KUEHNE, citizens of the United States, residing at Houston, in the county of Harris and State of Texas, have invented a new and useful Winding-Drum, of which the following is a specification.

The present application relates to improvements in winding drums, the same being especially adapted to be used in connection with the winding drum shown in our co-pending application filed September 3, 1913, Serial No. 788,030, one object of the present invention, being the provision of coöperative means carried by the support for the axle and the drum, and one head of the drum, whereby the head is permitted the desired oscillatory movement at the beginning of the rotation of the drum in a forward or reverse direction, whereby the position of the cam for imparting the longitudinal sliding movement to the staves of the drum is changed relatively to the standard and whereby the offset portion of the cam 25 is thus placed in the proper position for reeling or unreeling the cable upon or off of the drum during the winding or unwinding action of the drum.

A further object of the present invention, 30 is the provision of a cam carrying member disposed for oscillatory movement in connection with the standard which supports the drum provided with a plurality of longitudinally slidable staves, whereby the relative position of the cam may be changed 35 to properly oscillate the staves to guide the cable to and from the drum during the winding and unwinding action of the cable, such action of the cam being automatic and 40 operated entirely due to the stress or pull placed upon the cable.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 50 within the scope of what is claimed without departing from the spirit of the invention.

In the drawings—Figure 1 is a longitu-

dinal sectional view through a complete drum and support. Fig. 2 is a section taken on line 2—2 of Fig. 1. Fig. 3 is a diagrammatic plan view of the periphery of the cam carrying member showing the shape of the cam slot for actuating the staves of the drum. Fig. 4 is a side elevation of one of the staves *per se*. Fig. 5 is a detail view 60 of an anti-frictionally supported stave.

Referring to the drawings, the numeral 1 designates the standard or hanger which has rotatably mounted therein, the drum carrying shaft 2, the head or member 3 being 65 rotatably mounted upon the shaft 2 independently of the hanger 1 and having the bearing sleeve 4 for properly supporting the same. The rim 5 constitutes a housing in connection with the outer periphery of 70 the cam carrying member 6 for the inner ends of the longitudinally slidable staves 10, said cam carried member being movable with the member 3 due to the fastening thereof by means of the screws or bolts 7. 75 The periphery of the cam carried member is concentric with the inner face of the flange or rim 5 of the member 3 and is provided with the cam slot 8 for the reception of the anti-frictional rollers 9 mounted one 80 to each stave 10, so that as the shaft 2 is rotated, the sleeve 12 which is keyed by means of the screws 13 to the shaft 2 will cause the rotation of the disk 11 to which are mounted and connected for sliding longitudinal 85 movement, through the instrumentality of the ribs 10', the staves 10 which constitute the cable receiving portion of the drum. Thus the staves are properly rotated, and as the cam carried member 6 is held stationary 90 with regard to the drum, the staves 10 have imparted thereto, the desirable longitudinal movement to cause the guiding projections 18 for the cable to be moved in the proper position for guiding the lead on or off 95 strand of the cable to and from the drum.

The head forming member 14 of the drum, is connected by means of pins 15 to the spool 12 so as to rotate with the shaft 2, the inwardly projecting rim 16 providing a 100 housing for the outer ends 17 of the staves 10 so that there is no possibility of the ends of the staves becoming entangled with the cable.

In order that the member 3 and consequently the cam carried member 6 may be automatically oscillated relatively to the standard 1 and shaft 2, and consequently the 5 stave carrying member 12, so as to place the operating portion 8' of the cam slot at different positions due to the unwinding and winding of the cable upon the drum, the member 3 is provided with a plurality of 10 threaded sockets 19 for the reception of the pins 20 and 21, the standard 1 being provided with the pin 22 disposed in the path to engage either one of the pins 20 or 21 and thus limit the distance of oscillation 15 of the member 3 and its cam carrying member 6.

A plurality of the threaded sockets 19 are provided so that the pins 20 and 21 may be positioned to permit of the members 3 20 and 6 being oscillated to a greater or less degree, the illustration shown in Fig. 2 permitting the members to oscillate two-thirds of a revolution while with six sockets shown, the smallest movement would be one-sixth 25 of a revolution.

As shown in Fig. 5, the staves 10^e, are each provided with a rib 10^d which corresponds to the ribs 10' heretofore described. A recess 10^e is provided in the under side 30 of the rib for the reception of the balls 23, which constitute a ball bearing support to permit of the easy longitudinal sliding of the stave. The balls 23 slide within the respective grooves 24 formed in the outer 35 surface of the periphery 25 of the drum consisting of the disks 11^a, said disk 11^a corresponding with the disks 11, but being connected by means of the plate 25 as shown. By this means, the grooves 24 lock the staves 40 10^e against circumferential movement, but permit the desired longitudinal sliding movement due to the cam 8.

This structure is especially adapted in connection with the use of large drums, 45 and also wherein the strain upon the staves during the winding and unwinding would be such as to bind each individual stave and render it difficult to produce the longitudinal sliding action necessary.

50 50 What is claimed is:

1. A winding drum, including a support having two heads, a cable receiving member journaled between the heads and having a plurality of longitudinally slidable staves, 55 the ends of which are housed within the heads, a section of a cable guiding flange carried by each stave, one head being provided with a cam groove, and means carried by the adjacent end of each stave for engaging 60 the cam groove, whereby as the drum is rotated, the staves have successive longitudinal sliding movement imparted thereto.

2. A winding drum including a support having two heads, a cable receiving member

journaled between the heads and having a 65 plurality of longitudinally slidable staves, the ends of which are housed within the heads, a section of a cable guiding flange carried by each stave, one head being provided with a cam groove, and a pin and 70 roller carried at the end of each stave and for engagement with the cam groove, whereby as the drum is rotated, the staves have successive longitudinal sliding movement 75 imparted thereto.

3. A winding drum, including a support having two recessed heads, a shaft journaled through the support, a cable receiving drum having a plurality of longitudinally slidable staves, keyed to the shaft, the ends of the 80 staves being housed within the heads, a section of a cable guiding flange carried by each stave, an annular member seated within the recess of one head and provided with a cam groove, and a projection carried by 85 each stave for fitting in the cam groove, whereby as the drum is rotated, the staves have successive longitudinal movement imparted thereto.

4. A winding drum, including a support, 90 a shaft rotatably mounted therein, a cable receiving member having a plurality of longitudinally slidable staves keyed to the shaft, a cam for actuating the staves to impart longitudinal movement during the rotation of the shaft and staves, an oscillatory member upon which said cam is formed, mounted upon the shaft and in engagement with the staves, and co-operable means carried by said member and the standard for 100 limiting the oscillation of the cam carried member and for varying the position of the cam relatively to the standard.

5. A winding drum, including a standard, 105 a shaft rotatably mounted therein, a cable receiving member keyed to the shaft and having a plurality of longitudinally slidable staves constituting the cable receiving surface thereof, a cam carrying member mounted for oscillation upon the shaft adjacent 110 one end of the staves, means carried by the staves for engaging the cam whereby as the shaft is rotated, the staves have imparted longitudinal movement thereto, and co-operative means carried by the cam carried 115 member of the standard for limiting the oscillation of the said member during the winding and unwinding rotation of the drum, whereby the position of the cam is automatically shifted.

6. A winding drum, including a support, 120 a shaft rotatably mounted therein, a spool shaped member having a plurality of recesses formed in the peripheries of said member, a plurality of staves, one to each aligned pair of recesses, mounted for longitudinal movement relatively to the spool shaped member, a section of a cable guiding 125

flange carried by each stave, anti-frictional means between the staves and the spool shaped member, and a cam for actuating the staves to impart successive longitudinal movement thereto during the rotation of the shaft, the spool shaped member, and staves.

5 In testimony that we claim the foregoing

as our own, we have hereto affixed our signatures in the presence of two witnesses.

PHILIP H. VOIGT.
OSCAR C. KUEHNE.
